(Cl. D52—1)

To all whom it may concern:

Be it known that I, Raymond C. Webster, a citizen of the United States, residing at Kansas City, in the county of Jackson and State of Missouri, have invented a new, original, and ornamental Design for a Fluid Measuring Meter, of which the following is a specification, reference being had to the accompanying drawing, forming a part thereof.

Fig. 1 is a front elevational view of a fluid measuring meter, showing my new design.

Fig. 2 is a side elevational view thereof; and
Fig. 3 is a rear elevational view thereof.

I claim:

The ornamental design for a fluid measuring meter, as shown.

RAYMOND C. WEBSTER.
